UNITED STATES PATENT OFFICE.

WILLIAM V. OOTHOUT, OF BROOKLYN, ASSIGNOR TO G. L. KELTY & CO.,
OF NEW YORK, N. Y.

DESIGN FOR GIMP.

SPECIFICATION forming part of Design No. 12,127, dated January 18, 1881.

Application filed December 9, 1880. Term of patent 3½ years.

To all whom it may concern:

Be it known that I, WILLIAM V. OOTHOUT, a citizen of the United States, residing at the city of Brooklyn, in the county of Kings and State of New York, have invented certain new and useful Improvements in Designs for Gimp; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

The features of my design consist of a figure representing a series of flat, hollow squares resting at equal distances from each other on the body of the gimp, and a bar between each hollow square, parallel to them and crosswise of the body or face of the gimp, and the entire length of the gimp traversed by a belt running under two of the bars of the hollow square and over the center of the bar which lies between them. The edges of the gimp project a little beyond the squares and beyond the ends of the straight bar that rests between.

In the accompanying photograph, A is the body of the gimp. B represents the hollow square. C represents the bars between the 30 hollow squares. D is the belt traversing the body of the gimp and running under two of the bars of the hollow squares and over the center of the bar C between.

Having described my invention, what I 35 desire to secure by Letters Patent is—

A design for gimp, consisting of a figure representing a series of hollow squares, B, resting at equal distances from each other on the face or body A of the gimp, with a straight 40 bar, C, resting between each square, and a belt, D, traversing the entire length of the face of the gimp, running under the two cross-bars of the hollow square and over the center of the straight bar C that lies between, substantially 45 as shown.

In testimony whereof I affix my signature in presence of two witnesses.

WILLIAM V. OOTHOUT.
